UNITED STATES PATENT OFFICE.

GARTH G. GILPIN, OF RIVERSIDE, ILLINOIS, ASSIGNOR, BY MESNE ASSIGNMENTS, TO
RAILWAY METAL PRODUCTS COMPANY, A CORPORATION OF DELAWARE.

FREIGHT-CAR DOOR.

Original application filed October 23, 1925, Serial No. 64,467. Divided and this application filed
February 10, 1926. Serial No. 87,264.

Side doors of railway freight cars usually move horizontally to open or close the door opening, thus eliminating the possibility of interference with a car on an adjacent track 5 or other projection. Such a door is hung by hangers at its upper edge to the side plate of the car or is supported by brackets at its bottom edge to the side sill of the car. Rollers or other anti-friction means are generally used in such hangers or brackets. Sometimes a lower track is used and rollers are mounted in the lower edge of the door. Side doors should be stronger in their lower portion because of the heavier loads at this 15 part and also because it is subjected to more frequent impacts.

When in closed position the side door is a part of the retaining wall and as such must retain the load and also withstand the 20 impact of the lading due to rough track and rough train operation. These forces tend to bulge the door and if it deflects it binds in the associated parts on the car, making it very difficult to open, and if the door is 25 bent, it is also difficult to close, which difficulties have caused several types of so-called "door openers and closers" to be used. A door must be very strong to resist bending.

30 A side door is subject to severe impacts by being closed quickly and forcibly, which impacts are theoretically distributed along its entire front edge by a stop on the car body. However, if the door (or car) is not 35 square the impacts are received either on the top or bottom corner of the door. These doors are also jammed into the back stop upon being opened. It frequently happens that the cars are moved with the doors not fastened so that they are slammed back and forth against the front and back stops, respectively, by the movement of the train. When the door is closed its inertia causes a 40 severe tug or pull upon the fastening means, causing a severe local stress at this point. These several forces distort the door so that it does not properly fit the weather proofing means which are provided on the car, resulting in a leaky car and damage claims. 45 (A door must also prevent sparks from the locomotive entering the car.) Therefore, a door must be capable of preserving its rectangularity.

Any resistance to buckling tends to resist distortion. 55

An object of the invention is to so form a metallic plate and attach it to a metallic frame of a railway car door that it reinforces the door against distortion, bending and buckling, and furthermore, strengthens 60 the door as a retaining wall.

Another object of the invention is to so form a metallic plate adjacent the frame that it reinforces the frame and becomes 65 a part of it.

Another object of the invention is to support the door of the car (either at top or bottom) and also to anchor the door fastenings to other parts of the door than the comparatively thin metallic body plate. 70

Another object is to make the door very strong in its lower portion and comparatively light in its upper portion.

The door may be made of one or a plurality of sheets as desired. 75

In the drawings:

Fig. 1 shows the door.

Fig. 2 is a section on line 2—2 of Fig. 1.

Fig. 3 is a section on line 3—3 of Fig. 1.

Fig. 4 shows a modified form. 80

Fig. 5 is a section on line 5—5 of Fig. 4.

The associated parts of the door may be secured together by rivets, welding or any other convenient means.

The door comprises a rectangular frame 85 consisting of four angular members 30, 31, 32 and 33, attached together at its corners, if desired by any convenient means. Each angular member has an arm 37 projecting inwardly toward the door and a laterally 90 projecting arm 38 perpendicular to the plane of the door. The main body of the door comprises a plurality of sheets secured together to form a panel, with the outer sides and ends of this panel secured to the inwardly projecting arm 37 by rivets, welding or other convenient means. The lower metallic sheet 34 is provided with an embossment forming a continuous web 35 adjacent the frame on three sides, which web 100 has an outwardly extending flange 36 secured to the inwardly projecting arms of the frame members. The laterally extending arm 38 of the frame member and the web 35 of the plate thus form the opposite 105 flanges of a channel section.

The upper sheet 40 of the panel is flat and preferably of thinner material than the lower sheet. This upper sheet is also secured to the inwardly projecting arms of the frame 5 members.

When my construction is used in a top supported door I provide a reinforcing plate 62 inside the door behind the door hanger and a horizontal bar 63 just below the re- 10 inforcing plate also on the inside of the door, crossing the plate and secured to the opposite frame members. The door hanger is also preferably secured to this plate and bar.

In Figs. 4 and 5 the upper flat plate 40 is reinforced on the inside by bars 64—65 which not only prevent the flat plate from buckling but also brace the door against distortion. These bars may be made of one continuous bar.

20 The embossed plate is reinforced by a U-shaped stiffener 50 which crosses the embossment and is flattened out (and preferably flared out) at its ends and secured to the opposite frame members and preferably 25 also to the opposite flanges of the door plate. The stiffener is provided with lateral flanges 51 secured to the door plate. The stiffener or stiffeners may be located as desired.

This is a division of my co-pending application Serial No. 64,467, filed October 23, 1925.

I claim:

1. A door for a railway freight car comprising a rectangular frame made of angular 35 members having inwardly projecting arms, a metallic plate having an embossment forming a continuous web adjacent said frame, said web provided with an outwardly ex- 40 tending flange secured to the bottom and vertical frame members, and a flat metallic sheet forming the upper part of the door secured to the top and vertical frame members and also secured to said plate.

2. A door for a railway freight car comprising a rectangular frame made of angular 45 members having inwardly projecting arms, a metallic plate having an embossment forming a continuous web adjacent said frame, said web provided with an outwardly ex- 50 tending flange secured to the bottom and vertical frame members, and a flat thinner metallic sheet forming the upper part of the door secured to the top and vertical frame members and also secured to said plate.

55 3. A door for a railway freight car com-

prising a rectangular frame made of angular members having inwardly projecting arms, a metallic plate having an embossment forming a continuous web adjacent said frame, said web provided with an outwardly 60 extending flange secured to the bottom and vertical frame members, a flat metallic sheet forming the upper part of the door secured to the top and vertical frame members, and a horizontal stiffener secured to the outside 65 of said embossed plate with its ends fastened to the vertical members.

4. A door for a railway freight car comprising a rectangular frame made of angular members having inwardly projecting arms, a 70 metallic plate having an embossment forming a continuous web adjacent said frame, said web provided with an outwardly extending flange secured to the bottom and vertical frame members, a flat thinner metallic sheet forming the upper part of the door secured to the top and vertical frame members, and a horizontal stiffener secured to the outside 75 of said embossed plate with its ends fastened to the vertical members. 80

5. A door for a railway freight car comprising a rectangular frame made of angular members having inwardly projecting arms, a metallic plate having an embossment forming a continuous web adjacent said frame, 85 said web provided with an outwardly extending flange secured to the bottom and vertical frame members, a flat metallic sheet forming the upper part of the door secured to the top and vertical frame members, and a horizontal stiffener secured to the inside 90 of said flat sheet with its ends fastened to the vertical members.

6. A door for a railway freight car comprising a rectangular frame made of angular 95 members having inwardly projecting arms, a metallic plate having an embossment forming a continuous web adjacent said frame, said web provided with an outwardly ex- 100 tending flange secured to the bottom and vertical frame members, a flat metallic sheet forming the upper part of the door secured to the top and vertical frame members, a horizontal stiffener secured to the outside of 105 said embossed plate with its ends fastened to the vertical members, and a horizontal stiffener secured to the inside of said flat sheet with its ends fastened to the vertical members.

GARTH G. GILPIN.
